ROBERT D. EVANS, OF WILKINSBURG, PENNSYLVANIA, ASSIGNOR TO WESTINGHOUSE ELECTRIC & MANUFACTURING COMPANY, A CORPORATION OF PENNSYLVANIA.

BALANCE INDICATOR.

Application filed September 19, 1922. Serial No. 589,271.

My invention relates to indicating means and particularly to means for indicating unbalanced conditions of telephone and power circuits.

5 The object of my invention is to provide a simple and effective means for readily detecting unbalance in electrical circuits and particularly in telephone circuits where inductive interference and other influences 10 render the lines noisy.

In telephone and other communication circuits, the system is considered balanced when the two sides of a circuit have equal linear impedance and equal shunt admittance to 15 ground. This balance may be disturbed by contact of the conductors with trees and other grounded objects, as well as by other factors. If a potential be applied to an unbalanced circuit, unbalance currents will be 20 produced.

A balanced communication circuit will be unaffected by the inductive interference of a power circuit. However, an unbalanced power circuit will produce additional losses 25 in an unbalanced telephone circuit.

If balanced voltages are applied to an unbalanced power circuit, some current may be caused to flow in the earth. Under such conditions, since there is a relatively great 30 distance between the outgoing and the return currents, the effect on adjacent communication circuits will be relatively greater.

Unbalance causes noise in the telephone apparatus and renders conversation difficult, 35 if not impossible.

The condition of unbalance may readily be corrected, if the same be known, but, to the best of my knowledge, no device so simple and effective as the one herein proposed has 40 heretofore been suggested for determining unbalance.

In practicing my invention, I provide means whereby a section of the circuit under test may be included in a static network, 45 which is normally balanced under balanced conditions in the circuit, and means connected to the network for determining unbalance by a comparison of noises.

The single figure of the accompanying 50 drawing is a diagrammatic view of a device embodying my invention, together with the circuit connections therefor.

The device comprises, in general, a telephone receiver 1, a standard tone generator

2, a resistor 3 for varying the magnitude of 55 the current generator by the device 2, impedance devices 4 and 5 that are connected to a circuit 6 to be tested and a double-throw, three-pole switch 7. The generator 2 generates an alternating or pulsating current at 60 audible frequency—for instance, 800 cycles.

The impedance devices 4 and 5, preferably 65 resistors, are connected across the conductors of the circuit 6 at a predetermined distance from each other. The resistor 5 is connected from its mid-point to ground through a conductor 8. The resistor 4 is adapted to be connected, in one position of the switch 7, from its midpoint to ground, through a conductor 9, through one pole 10 of the switch 70 7, a conductor 11, the standard tone generator 2 and a conductor 12.

The receiver 1 is adapted to be connected, in one position of the switch 7, to the conductors of the circuit 6, through conductors 75 14, poles 15 and 16 of the switch 7 and conductors 17.

In the other position of the switch 7, the receiver 1 and the generator 2 are connected 80 through the resistor 3.

With the above-described arrangement, when the circuit 6 is balanced, there will be no current flow in the conductors 17 and, consequently, there will be no effect on the receiver 1 when the switch 7 is closed in its 85 upper position.

However, under unbalanced conditions, a current will flow in the conductors 17 and a tone corresponding to the current generated by the device 2 will be heard in the 90 receiver 1. The degree of unbalance will determine the distinctness of the sound heard in the receiver 1. This sound may be directly compared with the sound in the same pitch but of known magnitude by 95 moving the switch 7 to its lower closed position. The magnitude of the sound used for comparison is adjusted by means of the variable resistor 3. This resistor is suitably calibrated so that when the sounds heard in the receiver 1 for both positions of the switch are equal, an indication is provided of the degree of unbalance of the telephone line 6.

Since the pitch of the sounds heard in 105 both the upper and lower positions of the switch 7 will be the same, the strength or distinctness of the sounds may be readily

compared. Hence, the magnitude of the fault may be determined and corrected accordingly.

My invention may be modified by employing different values of the impedance. For instance, this impedance may be proportioned to represent a circuit of infinite length. The impedance may approach infinite values, in which case the effect of capacity unbalance of the circuit 6 would be indicated more clearly. Also, the impedance may approach zero value, in which case the effect of series unbalance of the conductors would be indicated more clearly.

15 While I have shown and described a particular form of my invention, changes and modifications may be made therein without departing from the spirit and scope thereof, as set forth in the appended claims.

20 I claim as my invention:

1. In a device for detecting unbalance in an electric circuit, the combination with a variable-circuit generator having one terminal connected to ground, of a variable resistor, a pair of impedance devices con-

nected across the conductors of said circuit, one of said impedance devices being grounded at the mid point thereof, a telephone receiver, and switching means for connecting the receiver to the generator 30 through said resistor and for connecting the receiver across the conductors of said circuit between the impedance devices and connecting the other terminal of the generator to the mid point of the other impedance 35 device.

2. In combination, a variable-current generator, an indicating device, a circuit, an impedance bridged across said circuit, and means for connecting said generator to the 40 midpoint of said impedance and said device to said circuit, said means also permitting the independent connection of said device to said generator through a local circuit of variable resistance.

45 In testimony whereof, I have hereunto subscribed my name this 15th day of September, 1922.

ROBERT D. EVANS.

CERTIFICATE OF CORRECTION.

Patent No. 1,624,484.

Granted April 12, 1927, to

ROBERT D. EVANS.

It is hereby certified that error appears in the printed specification of the above numbered patent requiring correction as follows: Page 2, line 23, claim 1, for the compound word "variable-circuit" read "variable-current"; and that the said Letters Patent should be read with this correction therein that the same may conform to the record of the case in the Patent Office.

Signed and sealed this 17th day of May, A. D. 1927.

Seal.

H. J. Moore,
Acting Commissioner of Patents.
